DESIGN FOR A PORTABLE TYPEWRITER

Richmond L. Chipman, Jr., Montclair, N. J., and
Joseph Lee Sweeney, New York, N. Y., assignors
to Bates Laboratories, Inc., New York, N. Y.

Application April 8, 1937, Serial No. 68,637

Term of patent 14 years

To all whom it may concern:

Be it known that we, Richmond L. Chipman, Jr., a citizen of the United States, residing at Montclair, New Jersey, and Joseph Lee Sweeney, a citizen of the United States, residing at New York, New York, have invented a new, original, and ornamental Design for Portable Typewriters, of which the following is a specification, reference being had to the accompanying drawing, forming part thereof.

Fig. 1 is a perspective view of a portable typewriter, showing our new design; and Fig. 2 is a side elevational view thereof.

The conventional number of keys are used, the dotted line showing of keys in Fig. 1 being merely for convenience of illustration.

The invention resides in the parts shown in full lines.

We claim:

The ornamental design for a portable typewriter, as shown and described.
